(57) **CLAIM**

The ornamental design for a pot as shown and described.

DESCRIPTION

FIG. 1 is an axonometric view of a pot showing my new design;

FIG. 2 is a front view thereof;

FIG. 3 is a left-side view thereof;

FIG. 4 is a back view thereof;

FIG. 5 is a right-side view thereof;

FIG. 6 is a top view thereof; and,

FIG. 7 is bottom view thereof.

The broken lines depict portions of the pot that form no part of the claim.

1 Claim, 7 Drawing Sheets
